(57) **CLAIM**

The ornamental design for a drip shield for a vehicle storage compartment, as shown and described.

DESCRIPTION

FIG. 1 is a top perspective view of a first embodiment of a drip shield for a vehicle storage compartment;

FIG. 2 is a bottom perspective view of the drip shield of FIG. 1;

FIG. 3 is a first side elevation view of the drip shield of FIG. 1;

FIG. 4 is a first end elevation view of the drip shield of FIG. 1;

FIG. 5 is a second side elevation view of the drip shield of FIG. 1;

FIG. 6 is a second end elevation view of the drip shield of FIG. 1;

FIG. 7 is a top plan view of the drip shield of FIG. 1;

FIG. 8 is a bottom plan view of the drip shield of FIG. 1;

FIG. 9 is a top perspective view of a second embodiment of a drip shield for a vehicle storage compartment;

FIG. 10 is a bottom perspective view of the drip shield of FIG. 9;

FIG. 11 is a first side elevation view of the drip shield of FIG. 9;

FIG. 12 is a first end elevation view of the drip shield of FIG. 9;

FIG. 13 is a second side elevation view of the drip shield of FIG. 9;

FIG. 14 is a second end elevation view of the drip shield of FIG. 9;

FIG. 15 is a top plan view of the drip shield of FIG. 9; and,

FIG. 16 is a bottom plan view of the drip shield of FIG. 9.

The broken lines show portions of a drip shield for a vehicle storage compartment, which form no part of the claimed design. The parallel “dash-dot” broken lines show a symbolic break in the claimed design. Anything that appears between the “dash-dot” parallel lines forms no part of the claimed design.
